HOUSED TYPE OF DROP-OUT FUSE

Alwin G. Steinmayer, Milwaukee, and William O. Schultz, South Milwaukee, Wis., assignors to Line Material Company, South Milwaukee, Wis., a corporation of Delaware

Application March 15, 1934, Serial No. 715,668

20 Claims. (Cl. 200—127)

This invention relates to a housed type of drop-out fuse.

Objects of this invention are to provide a housed type of drop-out fuse in which the casing is provided with stationary contacts normally engaged by the spaced contacts of the fuse, such as an expulsion fuse, in which the fuse and door are independently supported from the casing in such a manner that when the fuse blows, the door and fuse will rock outwardly away from the casing and upwardly as it is hinged at the top and the fuse, which was detachably attached to the door, sliding downwardly and detaching itself from the door and from the upper catch which normally restrains the fuse, and thereafter rocking outwardly and downwardly, the door swinging back towards closed position.

Further objects are to provide a drop-out fuse in which all of the live parts are completely enclosed in the housing, in which all contacts of the fuse tube as well as the hinge support for the fuse tube are electrically dead when the fuse has rocked to its down position, in which the door automatically tends to close and protect the live parts within the housing from the weather after the fuse has blown, and in which the contacts of the fuse tube do not break contact with the stationary contacts of the housing until the circuit has been interrupted by the blowing of the fuse link within the fuse tube, thereby avoiding arcing at the contacts, a certain interval of time elapsing before the breaking of the contacts occurs, thereby giving ample time for the fuse to clear itself, and to provide a construction which has the advantages of both a drop-out fuse and a housed fuse.

Further objects are to provide a construction in which the fuse tube is hinged adjacent its lower end by link mechanism restrained against opening movement by the fuse link, in which the fuse tube is biased towards open position, in which latching or restraining means are provided for the upper end of the fuse tube which automatically locks the fuse in circuit closing or operative position, in which means are provided for opening such latching means so that the fuse can be rocked to open position and thus act as a cut-out, and generally to provide a construction which may be as freely handled as an unhoused type of fuse.

In certain forms that the invention may take, additional objects are to provide spring means for holding the door elevated to provide the utmost freedom for the lineman, and to provide means which can be operated by a fuse pole or switch

stick for unlatching the fuse and rocking it to open position.

In other forms that the invention may take, further objects are to provide a novel construction of door such that the door forms an insulating handle for releasing the latching means and also for lifting the fuse from its supporting means during removal, or for replacing a new fuse, and to provide a construction in which the lineman or operator is practically forced to remove the door by simply unhooking it, thereby placing in his hand an insulating manipulating handle that acts as a switch stick or fuse pole and thus acting, in effect, as an inherent safety device for the protection of the operator.

Further objects are to provide a housed type of drop-out fuse which is of simple construction, which is practical, which may be easily re-fused or otherwise easily handled.

Embodiments of the invention are shown in the accompanying drawings, in which:—

Figure 1 is a vertical sectional view showing one form of the invention, such view showing the parts in operative position in full lines, and showing, in dotted lines, successive positions, as the fuse drops out.

Figure 2 is a sectional view on the line 2—2 of Figure 1.

Figure 3 is a bottom view of the construction shown in Figure 1.

Figure 4 is a fragmentary view of the lower part of the device, such view being similar to Figure 1, but with the fuse tube and door removed for the sake of clearness.

Figure 5 is a vertical sectional view, with parts broken away, showing a modified form of the invention, such view showing, in dotted lines, the fuse in its lowermost position and in the position it assumes during removal or replacement, such view further showing, in dotted lines, the positions assumed by the door when the fuse tube is being manipulated.

Figure 6 is a fragmentary face view of the lower portion of the door, of the type shown in Figure 5.

Referring to the drawings, particularly Figures 1, 2, 3, and 4, which show one form of the invention, it will be seen that a casing 1 of porcelain or similar material is provided with a door 2 which may be of a phenol condensate compound, or other suitable insulating material. This door is pivotally mounted, as indicated at 3, adjacent its upper end and is provided with an inwardly extending upper portion ending in a flat cam face 4.

55

This projecting portion is adapted to depress a holding spring 5 which is a relatively heavy leaf spring supported from the upper terminal member 6 of the casing and the flat face 4 is 5 adapted to engage the upper face of the spring 5 when the door is rocked to an approximately horizontal position, as indicated in the dotted lines in the upper portion of Figure 1, to thereby hold the door open and extend it outwardly from 10 the casing. The casing is provided with the upper terminal member 6 mentioned hereinabove and the lower terminal member 7, and is preferably provided with a barrier 8 which may be integrally formed and which is located intermediate the upper and lower terminals. These upper 15 and lower terminals respectively carry brush contacts 9 and 10 which constitute yielding stationary contact members and respectively engage the spaced contacts 11 and 12 carried adjacent the upper and lower portion of the expulsion fuse tube 13. The upper terminal member of the casing also carries a forwardly projecting stop 14 which when the fuse is in its operative position, as shown in full lines in Figure 1, is located above 20 the upper contact 11 of the fuse and is adapted to resist the upward pressure due to the reaction of the fuse when the fuse blows.

It is to be noted further from Figure 1 that the fuse tube carries an intermediate collar or 30 block 15 to which the lower contact 12 of the fuse is pivoted. This lower contact 12 in reality is a pivoted link or lever which has a bifurcated upper end provided with ears 16 pivoted, as indicated at 17, on opposite sides of the block 15.

35 This link 12 is provided with a thumb nut 18 which clamps the fuse link 19, joining the upper and lower contacts in the usual manner, to the lever 12 and thus retains the lever in the position shown in full lines in Figure 1 until the fuse link is ruptured, at which time the contact lever 12 and the fuse tube 13 may have relative motion. This contact lever 12 is provided with trunnions 20 which fit within the hook-shaped hinge members 21, such hinge members being provided with 40 inwardly projecting stops 22, see Figures 1, 3, and 4, which are engaged in the final downward motion of the mechanism by the laterally projecting feet or bottom ears 23 of the contact lever 12.

The door 2 is provided with an inwardly projecting portion 24, see Figure 3, which carries a locking plate or catch 25. The collar or block 15 carried by the fuse tube carries forwardly projecting spring arms 26, each of which is provided with an inwardly turned portion 27. These inwardly turned or bent portions snap over the projecting ends of the latch plate 25 and thus temporarily lock the fuse tube to the door. However, it is to be noted that when the fuse blows, the joint action of the latch plate 25 and 55 the portions 27 of the spring arms 26 guide the fuse tube with reference to the door when the fuse tube moves downwardly after blowing of the fuse. If desired, these spring arms may be formed of a strap or band, as indicated in Figure 3, which surrounds the block 15. Obviously when the fuse is in place, the door may be closed or opened by exerting sufficient pressure on the door, preferably by catching it with a switch stick or fuse stick adjacent the lower projecting portion, such portion constituting a rounded lower end 28, see Figure 1. Obviously, the door may be closed by merely pressing it inwardly, the spring arms 26 being spread by the plate 25 and snapping back into locking position as shown in 60 Figure 3.

Additionally, it is to be noted that when the contact lever 12 is released by the blowing of the fuse link 19, that the door and fuse tube both rock outwardly, as shown in Figure 1, and the spring arms 26 slide downwardly out of engagement with the latching plate 25, the fuse finally rocking to the lower dotted line position and the door rocking towards closed position.

The upper contact of the fuse is provided with a pair of projecting ears 29, see Figures 1 and 2, 10 which are provided with slanting cam faces on their front and rear sides. These ears slide in between the inturned portions 30 of upper spring arms 31 carried by the upper terminal member 6. As may be seen from Figures 1 and 2, the 15 inner ends of these inturned portions 30 of the spring arms are provided with downwardly and forwardly slanting faces 32 which are positioned in front of the ears 29 when the fuse is in operative position, as shown in Figures 1 and 2. However, when the lower end of the fuse rocks outwardly, due to the release of the contact lever 12 by the rupturing of the fuse link, the fuse may 20 slide downwardly with respect to the arms 30 and may thus disengage itself from the upper 25 latching means. Obviously when a new fuse is put into operation, it is merely necessary to rock it into vertical position after having hooked the trunnions 20 into the hinge supporting members 21, the spring arms 31 spreading and allowing the 30 ears 29 to snap back of the inner faces 32 of the inturned portions 30, see Figure 2.

It is apparent, therefore, that the door may be opened or closed independently of the fuse and that the fuse, when the fuse link is blown, will 35 drop downwardly and outwardly, the door swinging outwardly and allowing the discharge of the fuse tube and subsequently swinging towards closed position. It is sometimes necessary to remove the fuse tube manually. This is readily 40 accomplished by providing spreading means consisting of a pivoted lever having an upper cam portion 33 and a lower hooklike portion 34 adapted to be engaged by a switch stick to thereby rock the cam portion 33 downwardly. This cam portion 33 or spreading portion is provided with cam faces 35 which engage the inwardly projecting portions 30 of the upper spring arms and thereby spread such arms. Obviously, when the hook of a switch stick is hooked into the hook-shaped 50 portion 34 of the spreader or releasing means, the cam portion 33 is rocked downwardly, thereby releasing the upper end of the fuse, and continued pulling on the switch stick will rock the upper end of the fuse outwardly clear of the upper spring 55 arms.

The fuse may be removed by unhooking the trunnions 20 from the hinge means 21, see Figures 1 and 4, it being noted that the hinge means is electrically dead when the fuse is opened as it is 60 distinct and separate from both stationary contacts and as the contact lever 12 is moved out of engagement with the stationary contact 10.

It is to be noted particularly that the yielding contact members 9 and 10 are deflected or tensioned when the fuse tube is in closed position, as shown in full lines in Figure 1, and that, therefore, they exert a spring pressure against the fuse tube which supplements the action of gravity and biases the fuse tube towards open position. 65 In addition to this, they follow their respective contacts 11 and 12 of the fuse tube outwardly a material distance at the initiation of the outward dropping motion of the fuse tube and thus maintain electrical contact for a material in- 70 75

terval of time so that the fuse tube will completely clear itself before the contacts are broken, thus avoiding arcing at the stationary contacts.

It is to be noted that the spring 5, see Figure 1, which locks with the flat face 4 of the door, materially assists a lineman in manipulating the fuse, as in re-fusing or during inspection, as it holds the door in its open position and allows free access to the interior of the casing.

10 The device may take other forms. For example as shown in Figure 5, the casing 36 may be provided with upper hocklike hinge means 37 which receive the pivot pin 38 carried by the upper portion of the door 39. The fuse tube 40 is provided with the intermediate block 41 and with the lower contact lever 42 which engages the lower brush contact 43, as previously described, and which is held in place by the fuse link 44.

This lower contact lever 42 is provided with 20 trunnions 45 which are removably received within the lower hinge member 46 and may be detached therefrom when the fuse has dropped to open position.

Similarly to the form previously described, the 25 door may be provided with a latch plate 47 which is received between the spring arms 48 carried by the collar 41 as previously described.

The upper contact 49 of the fuse tube engages 30 the upper stationary contact 50 of the casing in a manner similar to that previously described and is provided with ears 50' which fit behind the slanting faces 51 of the upper spring arms 52 similar to the previously described form. However, this upper contact member is provided with 35 a forwardly directed hook or ear 53 which is upwardly directed when the fuse is in its operative position, as shown in full lines in Figure 4.

The door 39 is detachable from the casing, as described, and is provided with a lower projecting portion which constitutes a handle and is formed with a pair of outwardly projecting ribs 54, most clearly shown in Figure 6. These ears are joined at their outer ends by a rounded web 55 which conforms approximately to the curvature of the fuse tube. Further, this projecting 45 handle portion is provided with a slot or opening 56 which is preferably provided with a bevelled face 57.

This door, it will be noted, is freely removable 50 from the casing by merely pulling it outwardly and thereafter unhooking the upper trunnions or pin 38 from the upper hook member 37 of the casing. Thereafter the door is reversed and the projecting portion is employed to engage the upper contact of the fuse and to spread the spring arms 52.

This is accomplished by hooking such projecting portion of the door over the hook 53, as shown 60 in the upper dotted line position for the door in Figure 5, the hook 53 of the upper contact of the fuse passing into the opening 56. The door is then rocked upwardly and the projecting portion enters between the spring arms 52 and spreads them in the same manner that the cam portion 33 of Figure 2 spreads the spring arms of that form of the invention. Thereafter the door is merely pulled forwardly, thereby pulling the upper end of the fuse forwardly and the fuse is rocked down to its outward position.

70 The door is now unlocked from the hook 53, placed below the tube, and thereafter re-engaged with the hook 53, as shown in dotted lines in Figure 5.

It will be seen that the fuse tube body rests 75 upon the web 55 and the extreme upper portion

of the contact of the fuse rests between the webs 54, while the hook portion 53 is interlocked with the door. The fuse may thereafter be lifted bodily upwardly and unhooked from the lower hinge members 46.

The fuse may be re-fused and replaced by the use of the door and thereafter the door is unhooked from the fuse tube and is used to push the fuse tube into closed position. Subsequently the door is itself hooked on its hinge supporting 10 means 37 and rocked to closed position.

It is to be particularly noted that in this form of the invention the door itself, formed of insulating material, constitutes the switch stick or fuse stick and is used in the manipulation of the 15 fuse so that the fuse can be opened, removed, or replaced by means of the door without requiring the lineman to carry a separate switch stick.

In addition to this, there is a further safety feature with this form of the invention in that the 20 lineman is practically compelled to remove the door in order to get at the fuse, as he would otherwise have to hold the door up with one hand whenever he attempted to reach the fuse. It is thus a reminder to the lineman that he must 25 remove the door and thereafter he finds himself with a fuse stick in his hands with which he can remove or manipulate the fuse.

Further than this, the projecting portion of the door forms a manipulating handle for the door 30 itself in opening or closing the door.

When the fuse blows, the lower end moves outwardly, thereby rocking the door outwardly and slips downwardly, thereby detaching itself from the door, as previously described, and subsequently rocks downwardly, the door thereafter 35 swinging to closed position and protecting the interior of the casing.

In this form of the invention no stops are employed in the hook supporting means 46 and the 40 fuse tube swings downwardly into a vertical position, as indicated in dotted lines in Figure 5. Obviously either form of the invention can provide for the complete downward swinging of the fuse tube as described in connection with the 45 form shown in Figure 5, or stops may be provided, as described in connection with the form shown in Figure 1. The door may either partially close or may be completely closed, as described in the two forms of the invention. Under all 50 conditions, however, the fuse drops out from the casing in the manner described and the door moves towards closed position, thereby substantially closing the housing in the one case and fully closing the housing in the other, though 55 either form may be employed with either of the two forms shown.

It will be seen that the construction is simple and is practical and that the fuse is wholly reliable in operation.

Although this invention has been described in considerable detail, it is to be understood that such description is intended as illustrative rather than limiting, as the invention may be variously embodied and is to be interpreted as claimed.

We claim:

1. A housed type of drop-out fuse comprising a casing having stationary contacts, a door for said casing, a fuse tube movable outwardly to inoperative position and having spaced contacts engaging said stationary contacts when said fuse tube is in operative position, a fuse link normally electrically joining said spaced contacts, mechanism normally holding said fuse tube in operative position and releasable when said fuse link 75

blows, and means independently supporting said door and fuse tube from said casing, a portion at least of said door being located in the path of travel of said fuse tube, said fuse tube when said fuse blows moving to inoperative position and moving said door outwardly during a part at least of the motion of the fuse tube to inoperative position, said door being pivotally supported above its center of gravity, whereby said door will tend to close after said fuse tube has moved to inoperative position.

2. A housed type of drop-out fuse comprising a casing having stationary contacts, a door hinged adjacent its upper end to said casing, a fuse tube hinged adjacent its lower end to said casing and adapted to move downwardly and outwardly from said casing and from said door, the lower portion of said door being located in the path of travel of said fuse tube, said fuse tube having spaced contacts normally engaging said stationary contacts and having a fuse link electrically joining said spaced contacts, and releasable mechanism controlled by said fuse link for holding said fuse tube in normal position, said fuse tube upon blowing of said fuse moving said door outwardly during a part at least of the motion of said fuse tube towards inoperative position, the hinged portion of said door being above the center of gravity of said door, whereby said door is biased towards closed position and tends to close after said fuse tube has moved downwardly and outwardly.

3. A housed type of drop-out fuse comprising a casing having stationary contacts, a door hinged adjacent its upper end to said casing, a fuse tube hinged adjacent its lower end to said casing and adapted to move downwardly and outwardly from said casing and from said door, said fuse tube having spaced contacts normally engaging said stationary contacts and having a fuse link electrically joining said spaced contacts, releasable mechanism controlled by said fuse link for holding said fuse tube in normal position, the hinged portion of said door being above the center of gravity of said door, said door being biased towards closing position and tending to close after said fuse tube has moved downwardly and outwardly, the lower portion of said door being located in the path of travel of said fuse tube, said fuse tube upon blowing of said fuse moving said door outwardly through a portion at least of the travel of said fuse tube towards inoperative position, said door being normally movable to an elevated position, and means for releasably holding said door in elevated position.

4. A housed type of drop-out fuse comprising a casing having stationary contacts, a fuse tube having spaced contacts and having a fuse link electrically joining said spaced contacts, hinge link mechanism adjacent the lower part of said fuse tube for supporting said fuse tube from said casing and for guiding said fuse tube outwardly and downwardly, said mechanism being normally restrained by said fuse link, latch means normally holding the upper end of said fuse tube against outward motion, and a door hingedly supported adjacent its upper end from said casing, the lower portion of said door being located at the path of travel of said fuse tube, said fuse tube moving said door outwardly through a portion at least of the motion of said fuse tube to inoperative position, said door being biased towards closed position and moving towards closed position after said fuse tube has completed its travel towards inoperative position.

5. A housed type of drop-out fuse comprising a casing having stationary contacts, a fuse tube having spaced contacts and having a fuse link electrically joining said spaced contacts, hinge link mechanism adjacent the lower part of said fuse tube for supporting said fuse tube from said casing and for guiding said fuse tube outwardly and downwardly, said mechanism being normally restrained by said fuse link, latch means normally holding the upper end of said fuse tube against outward motion, and a door hingedly supported adjacent its upper end from said casing, the hinged portion of said door being above the center of gravity of said door, said door tending to swing closed after said fuse tube has moved to its down position, the lower portion of said door being located in the path of travel of said fuse tube, and said fuse tube releasing itself from said latch means by a downward motion and moving said door outwardly through a portion at least of the travel of said fuse tube towards inoperative position.

6. A housed type of drop-out fuse comprising a casing having stationary contacts, a fuse tube having spaced contacts and having a fuse link electrically joining said spaced contacts, hinge link mechanism adjacent the lower part of said fuse tube for supporting said fuse tube from said casing and for guiding said fuse tube outwardly and downwardly, said mechanism being normally restrained by said fuse link, latch means normally holding the upper end of said fuse tube against outward motion, a door hingedly supported adjacent its upper end from said casing, and means operable independently of the action of said fuse for releasing said latch means.

7. A housed type of drop-out fuse comprising a casing having stationary contacts, a door hinged to said casing, a fuse movably supported from said casing and having spaced contacts electrically joined by a fuse link, said fuse being movable from said casing and being restrained from movement by said fuse link, latch means normally holding said fuse with the spaced contacts in engagement with said stationary contacts and including spring fingers, said door being movable outwardly without disturbing said fuse tube, and means for spreading said spring fingers, whereby said fuse tube may be manually moved to open position.

8. A housed type of drop-out fuse comprising a casing having stationary contacts, a door hinged to said casing, a fuse movably supported from said casing and having spaced contacts electrically joined by a fuse link, said fuse being movable from said casing and being restrained from movement by said fuse link, latch means normally holding said fuse with the spaced contacts in engagement with said stationary contacts and including spring fingers, said door being movable outwardly without disturbing said fuse tube, and means for spreading said spring fingers, whereby said fuse tube may be manually moved to open position, the spreading means being carried by said fuse tube.

9. A housed type of drop-out fuse comprising a casing having stationary contacts, a door hinged to said casing, a fuse movably supported from said casing and having spaced contacts electrically joined by a fuse link, said fuse being movable from said casing and being restrained from movement by said fuse link, latch means normally holding said fuse with the spaced contacts in engagement with said stationary contacts and including spring fingers, said door being movable

- outwardly without disturbing said fuse tube, and means for spreading said spring fingers, whereby said fuse tube may be manually moved to open position, the spreading means being pivotally mounted on said fuse tube and including a cam member adapted to be rocked between said spring fingers. 5
10. A housed type of drop-out fuse comprising a casing having stationary contacts, a door hinged to said casing, a fuse movably supported from said casing and having spaced contacts electrically joined by a fuse link, said fuse being movable from said casing and being restrained from movement by said fuse link, latch means 15 normally holding said fuse with the spaced contacts in engagement with said stationary contacts and including spring fingers, said door being movable outwardly without disturbing said fuse tube, and means for spreading said spring fingers, 20 whereby said fuse tube may be manually moved to open position, the spreading means being carried by said door.
11. A housed type of drop-out fuse comprising a casing having stationary contacts, a door hinged to said casing, a fuse movably supported from said casing and having spaced contacts electrically joined by a fuse link, said fuse being movable from said casing and being restrained from movement by said fuse link, latch means 25 normally holding said fuse with the spaced contacts in engagement with said stationary contacts and including spring fingers, said door being movable outwardly without disturbing said fuse tube, and means for spreading said spring fingers, 30 whereby said fuse tube may be manually moved to open position, said door being formed of insulating material and having the spreading means formed as a unitary part of said door.
12. In a housed fuse, a casing having stationary contacts, a fuse tube having spaced contacts and having a fuse link electrically joining said spaced contacts, means for releasably holding said fuse tube in position with the spaced contacts engaging the stationary contacts, and a door for said 40 casing, said door being detachable from said casing and having means for releasing said fuse tube after said door has been detached from said casing.
13. In a housed fuse, a casing having stationary contacts, a fuse tube having spaced contacts and having a fuse link electrically joining said spaced contacts, means for releasably holding said fuse tube in position with the spaced contacts engaging the stationary contacts, and a door for said 50 casing, said door being detachable from said casing and having means for releasing said fuse tube and for interlocking with said fuse tube after said door has been detached from said casing, whereby said door constitutes a fuse stick 55 for manipulating said fuse tube.
14. A housed type of drop-out fuse comprising a casing having stationary contacts, a fuse tube having spaced contacts and having a fuse link electrically joining said spaced contacts, mechanism adjacent the lower portion of said fuse tube for normally supporting said fuse tube, said mechanism being normally restrained by said fuse link, a door movably related to said casing, and means carried jointly by said door and said 60 fuse tube for slidably connecting said fuse tube and door, whereby said fuse tube slides with respect to said door during at least a part of the travel of said fuse tube towards inoperative position upon blowing of said fuse.
- 75 15. A housed type of drop-out fuse comprising a housing having stationary contacts, a fuse tube assembly including pivotally mounted supporting means and a fuse tube carried by said supporting means and movable with respect to said supporting means, said fuse tube assembly having spaced contacts normally engaging said stationary contacts, said fuse tube assembly being movable outwardly from operative to inoperative position, a fuse link carried by said fuse tube electrically connecting said spaced contacts 10 and normally restraining said fuse tube assembly from moving from operative to inoperative position, and a door for said housing pivotally supported from said housing independently of said supporting means and arranged in the path of travel of said fuse tube assembly from operative to inoperative position, whereby said door will be moved towards open position while said fuse tube assembly is moving towards inoperative position. 20
16. A housed type of drop-out fuse comprising a housing having terminal members, a fuse tube assembly including a fuse tube and supporting means pivotally supported from said housing and movably supporting said fuse tube, said fuse tube 25 assembly being movable from closed position to open position outwardly from said housing, a fuse link carried by said fuse tube electrically connecting said terminal members and normally holding said fuse tube assembly against opening 30 movement, and a door supported from said housing independently of said supporting means and at a point remote from the pivot point of said supporting means, said door being arranged in the path of travel of said fuse tube assembly 35 from operative to inoperative position, whereby said door will be moved towards open position while said fuse tube assembly is moving towards inoperative position.
17. A housed type of drop-out fuse construction comprising a housing having terminal members, a fuse tube assembly including a fuse tube and supporting means pivotally carried by said housing and movably holding said fuse tube, a fuse link carried by said fuse tube electrically 40 connecting said terminal members and normally holding said fuse tube against motion with respect to said supporting means, said construction including latch means normally latching said fuse tube assembly in closed position, said fuse 45 tube assembly freeing itself from said latch means as said fuse tube moves with respect to said supporting means, and a door supported from said housing independently of said supporting means and at a point remote from the 50 pivot point of said supporting means, said door being arranged in the path of travel of said fuse tube assembly from operative to inoperative position, whereby said door will be moved towards open position while said fuse tube assembly is 55 moving towards inoperative position.
18. A housed type of drop-out fuse construction comprising a housing having terminal members, a fuse tube assembly including a fuse tube and supporting means pivotally carried by said housing and movably holding said fuse tube, a fuse link carried by said fuse tube electrically 60 connecting said terminal members and normally holding said fuse tube against motion with respect to said supporting means, said construction including latch means normally latching said fuse tube assembly in closed position, said fuse 65 tube assembly freeing itself from said latch means as said fuse tube moves with respect to said supporting means, and a door pivotally sup- 70
- 75 15. A housed type of drop-out fuse comprising

ported from said housing independently of said supporting means and at a point above the pivot point of said supporting means, said door being arranged in the path of travel of said fuse tube 5 assembly from operative to inoperative position, whereby said door will be moved towards open position while said fuse tube assembly is moving towards inoperative position.

19. A housed type of drop-out circuit interrupting device comprising a casing having stationary contacts, a door for said casing, an arcing tube movable downwardly to inoperative position, an expulsive conductor in said arcing tube normally establishing electrical connection between said stationary contacts, and current responsive means for releasing said arcing tube when said circuit interrupting device is subjected to an overload, said door being positioned in the path of movement of said arcing tube when said 10 arcing tube moves from operative to inoperative position whereby said door will be moved towards open position while said arcing tube is moving towards inoperative position.
20. A housed type of drop-out circuit interrupting device comprising a casing having stationary contacts, a door for said casing, an arcing tube movable downwardly to inoperative position, an expulsive conductor in said arcing tube normally establishing electrical connection between said stationary contacts, and current responsive means for releasing said arcing tube when said circuit interrupting device is subjected to an overload, said door being positioned in the path of movement of said arcing tube when said 15 arcing tube moves from operative to inoperative position whereby said door will be moved towards open position while said arcing tube is moving towards inoperative position, said door being pivoted independently of said arcing tube and swinging towards closed position after said arcing tube has moved to inoperative position.

20. A housed type of drop-out circuit interrupting device comprising a casing having stationary contacts, a door for said casing, an arcing tube movable downwardly to inoperative position, an expulsive conductor in said arcing tube normally establishing electrical connection between said stationary contacts, and current responsive means for releasing said arcing tube when said circuit interrupting device is subjected to an overload, said door being positioned in the path of movement of said arcing tube when said arcing tube moves from operative to inoperative position whereby said door will be moved towards open position while said arcing tube is moving towards inoperative position, said door being pivoted independently of said arcing tube and swinging towards closed position after said arcing tube has moved to inoperative position.
